COMBINED SUPPORT BRACKET AND SPRAY HEAD FOR A DISPENSER

Raymond E. Portyrafa, North Haven, Conn., assignor to Labranche Industries, Inc., New Bedford, Mass., a corporation of Massachusetts

Filed Nov. 15, 1967, Ser. No. 9,421

Term of patent 14 years

Int. Cl. D6—01

U.S. Cl. D33—30

FIGURE 1 is a perspective view of a combined support bracket and spray head for a dispenser embodying my new design;

FIGURE 2 is an exploded perspective view thereof;

FIGURE 3 is a top plan view of the spray head;

FIGURE 4 is a rear elevational view of the spray head;

FIGURE 5 is a front elevational view of the spray head;

FIGURE 6 is a side elevational view of the spray head; and

FIGURE 7 is a bottom plan view of the spray head.

The dominant features of my design reside in the portions shown in full lines, it being understood that the broken line representation of a container, an electric cord and a wall in FIGURE 1 is for purposes of illustration only.

I claim:

The ornamental design for a combined support bracket and spray head for a dispenser, as shown and described.
